UNITED STATES PATENT OFFICE.

PERLEY D. WARNER, OF KEWANEE, ILLINOIS.

BROODER.

Application filed July 10, 1926. Serial No. 121,580.

The present invention relates to a brooder for chicks and aims to provide a device of this nature capable of using an oil lamp as a source of heat without any danger of the 5 chicks becoming asphyxiated.

A very important object of the invention lies in the provision of an improved radiator unit for distributing the heat under a hood.

Another very important object of the 10 invention lies in the provision of a draft device which will tend to suck out of the room impure gases and set up a desirable circulation.

A further very important object of the 15 invention lies in the provision of a burner of this nature which is exceedingly simple in its construction, compact and convenient in its arrangement, strong and durable, inexpensive to manufacture, easy to assemble, 20 and disassemble, efficient and reliable in use, and otherwise well adapted to the purpose for which it is designed.

With the above and numerous other 25 objects in view as will appear as the description proceeds, the invention resides in certain novel features of construction, and in the combination and arrangement of parts as will be hereinafter more fully described and claimed.

30 In the drawings:—

Figure 1 is a sectional elevation of the 35 brooder embodying the features of my invention,

Fig. 2 is an enlarged detail vertical section taken substantially on the line 2—2 of Fig. 1,

Fig. 3 is a detail horizontal section taken 40 transversely and substantially on the line 3—3 of Fig. 2,

Fig. 4 is an enlarged detail vertical section taken through the lower portion of the 45 brooder, and

Fig. 5 is a horizontal section taken substantially on the line 5—5 of Fig. 4.

45 Referring to the drawings in detail, it will be seen that the numeral 5 denotes a casing having a hingedly mounted top 6 associated therewith. A pipe 7 leads from the bottom of the casing outwardly. An 50 oil burner of any suitable or preferred construction is designated by the numeral 8 and is disposed in the casing 5. A supply pipe 9 leads from the burner 8 through the pipe 7. As is clearly shown in Fig. 4, the burner 55 extends through the top 6, and may be regulated externally of the casing by suitable

well known means as is designated by the numeral 10.

A radiator is designated generally by the letter R and includes a bottom header 11 and 60 a top header, 12. These headers 11 and 12 are connected by a plurality of tubes 14 hinged in parallel spaced relation. The bottom header 11 has an enlarged opening 15 in its bottom from which extends an 65 annular flange 16 adapted to rest on the top 6 and provided with a prong 17 piercing a suitable aperture in the top 6. It is thus possible to swing the radiator for lifting a portion of the header from the top there- 70 of in order that access may be had to the wick of the burner for lighting the same, and putting the same out.

A pair of guides 18 are arranged on the 75 header 11 adjacent an opening 19 for receiving a transparent closure 20 which may be slid to an open or closed position. It will also be seen that access may be had to the wick end of the burner through this opening 19 if desired for lighting or unlighting 80 the burner. The radiator is swung as described above, more particularly trimming the wick and the like.

The upper header 12 is provided with a 85 frusto-conical extension 21 disposed upwardly and having an annular collar adjacent its smaller end as is indicated at 22. The smaller end of the frusto-conical extension 21 terminates in a cylindrical portion 23 over which is adapted to telescope the 90 lower end of the chimney pipe 24. A frusto-conical shaped hood 25 has its smaller upper end receiving the chimney pipe 24 and the collar 22 holds the hood in spaced 95 relation in the frusto-conical extension 21, and this hood extends down over the radiator R and the casing 5 terminating a distance from the floor on which the casing may be resting.

The chimney 24 terminates at its upper 100 end in a plurality of spaced lugs 26. A draft creating device D is associated with the upper end of the chimney pipe 24 and includes a drum 27, the upper 28 of which is provided with a central opening 29 receiving an upper chimney pipe 30. The lower end 31 of the drum 27 is provided with an opening 32 for receiving the chimney pipe 24. A rod 33 extends transversely across the upper portion of the drum 105 D and supports an inverted cup-shaped member 34, the lower open edge of which 110

is spaced from the bottom 31. The bottom end 31 is provided with an annular series of openings 35. The closed upper end of the inverted cup-shaped member 34 rests 5 on the top of the lugs 26.

When the burner is lighted, the air will circulate through the pipe 7, casing 5, header 11, tubes 14, header 12, chimney pipe 24, inverted cup-shaped member 34, drum 27 and chimney pipe 30 as may be followed clearly 10 in Figs. 1, 2 and 4 of the drawing. This circulation of the air caused by the draft will suck in foul air through the openings 35, thereby causing a circulation in the room 15 or the like in which the brooder may be placed. Thus foul air and obnoxious gases may be readily taken off.

It will also be seen that the radiator will 20 prove very efficient and will heat up the space in the hood 25 with a minimum expenditure of fuel in the burner. It will also be seen that the oxygen used up by the burner is not taken from the space within the hood 25. The device, therefore, is very efficient 25 and reliable in use.

It is thought that the construction, utility, and advantages of this invention will now 30 be apparent to those skilled in this art without a more detailed description thereof. The present embodiment of the invention 35 has been disclosed in detail, merely by way of example since in actual practice it attains the features of advantage enumerated as desirable in the statement of the invention and the above description.

It is apparent that numerous changes in 40 the details of construction, and in the combination and arrangement of parts may be resorted to without departing from the spirit or scope of the invention as hereinafter claimed, or sacrificing any of its advantages.

Having thus described my invention, what I claim as new is:—

1. A brooder of the class described including a casing for receiving a burner, a hood, a radiator in the hood comprising an upper and a lower header, a plurality of tubes connecting the headers, said lower header adapted to rest on the casing, said casing and said lower header being provided with communicating openings, a chimney pipe leading from and communicating with the upper header, a draft device associated with the said chimney pipe comprising a drum having its lower end provided with an opening through which the chimney pipe extends and its upper end provided with an opening, a chimney pipe extending into the opening of the upper end, a rod extending transversely of the drum, an inverted cup-shaped member supported by said rod so that its lower edge is spaced from the bottom end of the drum, said bottom end of the drum being provided with an annular series

of apertures, said inverted cup-shaped member being spaced from the first chimney pipe and the drum. 65

2. A brooder of the class described including a casing for receiving a burner, a hood, a radiator in the hood comprising an upper 70 and a lower header, a plurality of tubes connecting the headers, said lower header adapted to rest on the casing, said casing and said lower header being provided with communicating openings, a chimney pipe leading 75 from and communicating with the upper header, a draft device associated with the said chimney pipe comprising a drum having its lower end provided with an opening through which the chimney pipe extends and 80 its upper end provided with an opening, a chimney pipe extending into the opening of the upper end, a rod extending transversely of the drum, an inverted cup-shaped member supported by said rod so that the lower 85 edge is spaced from the bottom end of the drum, said bottom end of the drum being provided with an annular series of apertures, said inverted cup-shaped member being spaced from the first chimney pipe and 90 the drum, the upper end of the first chimney pipe terminating in a plurality of extensions spaced from one another and engaging the top of the inverted cup-shaped member. 95

3. A brooder of the class described including, in combination, a casing for receiving a burner, a radiator including a lower header and an upper header connected by a plurality of tubes, said lower header having an opening communicating with an opening in the casing on which the lower header rests, said upper header being provided with a frusto-conical extension disposed upwardly, a collar disposed exteriorly of said frusto-conical extension, a hood of frusto-conical formation extending over the radiator and casing and resting on said collar to be held in spaced relation to the frusto-conical extension of the upper header. 100

4. A brooder of the class described including, in combination, a casing for receiving a burner, a radiator including a lower header and an upper header connected by a plurality of tubes, said lower header having an opening communicating with an opening in the casing on which the lower header rests, said upper header being provided with a frusto-conical extension disposed upwardly, a collar disposed exteriorly of said frusto-conical extension, a hood of frusto-conical formation extending over the radiator and casing and resting on the collar to be held in spaced relation to the frusto-conical extension of the upper header, a pipe leading into the lower portion of the casing 110 115 120 125 from the exterior of the hood.

In testimony whereof I affix my signature.
PERLEY D. WARNER.
